No. 737,376.

Patented August 25, 1903.

UNITED STATES PATENT OFFICE.

JOSEF ENDER, OF LANDECK, GERMANY.

SHOOTING-SPECTACLES.

SPECIFICATION forming part of Letters Patent No. 737,376, dated August 25, 1903.

Application filed May 19, 1903. Serial No. 157,808. (No model.)

To all whom it may concern:

Be it known that I, JOSEF ENDER, a subject of the King of Prussia, residing at Landeck, Silesia, in the Kingdom of Prussia and Empire of Germany, have invented new and useful Improvements in Shooting-Spectacles, of which the following is a specification.

My invention relates to shooting-spectacles, and has for its object to so arrange an aiming-lens on the same that it may be adjusted relatively to the line of sight.

In the accompanying drawings I have represented these shooting-spectacles, Figure 1 being a rear view, and Fig. 2 a top view, of the same.

On the bow *b*, connecting the rims *a* of the spectacles, is furnished a pin *c*, on which a socket *d* may be adjustably secured by means of screws or the like. This socket *d* carries the aiming-lens *e*, which is so arranged that when the head is in an oblique position the line of sight will pass perpendicularly through the said lens.

In order to place the aiming-lens in such a position that the use of the shooting-spectacles may not become inconvenient, the rim *a* of the right eyeglass is pressed inward, this glass being ground with a corresponding recess. Thus the rim of the aiming-lens *e* can drop into the recess formed. 25 30

What I claim as my invention, and desire to secure by Letters Patent, is—

Shooting-spectacles of the character set forth, having an aiming-lens arranged to be adjustably fixed in a recess formed in the rim 35 of one of the glasses near the bow, substantially as herein described.

In testimony whereof I have signed my name to this specification in the presence of two witnesses.

JOSEF ENDER.
